UNITED STATES PATENT OFFICE.

DENNIS WILLIAM DALEY, OF PARKERSBURG, WEST VIRGINIA.

STILL AND WATER-HEATER.

1,116,804.

Specification of Letters Patent. Patented Nov. 10, 1914.

Application filed December 27, 1910. Serial No. 599,633.

To all whom it may concern:

Be it known that I, DENNIS W. DALEY, a citizen of the United States, residing at Parkersburg, in the county of Wood and State of West Virginia, have invented certain new and useful Improvements in Stills and Water-Heaters; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to a combined hot water heater and still and has for its object to provide a device of this class particularly adapted to be used for domestic purposes and which is so constructed and arranged that a supply of the distilled water is at all times available while at the same time the water for the domestic fixtures is heated to supply the said fixtures.

A further object of the invention is to provide a simple and efficient construction for distilling water and for heating a separate supply of water for the hot water fixtures.

A further object of the invention is to provide a combined hot water heater and still which is particularly simple in its construction, cheap and easy to manufacture and install, requiring a small space, strong, durable and efficient.

With these objects in view the invention consists in the novel combination of parts and particularly in the combination and arrangement of the hot water storage tank with the hot water tank containing the distilling coil.

The invention also consists in the novel arrangement of the feed tank and heater and a connection between the same to prevent the water from passing from the heater to the feed tank.

The invention further consists in the novel construction of the parts which provide for a separate supply of water to be distilled from the supply of water to the hot water fixtures.

The invention also consists in the novel construction and combination of parts which provides for distilling water and simultaneously heating a separate supply for the hot water fixtures.

The invention further consists in certain other novel details and combinations of parts all of which will be first fully described and afterward specifically pointed out in the appended claim.

Referring to the accompanying drawing: the figure is an elevation partly in vertical section illustrating the arrangement of the system.

Referring to the figure by reference numerals; 1 indicates a domestic boiler or storage tank, 2 a heater, 3 a steam tank, 4 a hot water tank and 5 the float or feed chamber. As will appear from the drawing the float chamber 5 is provided with a float valve 6 shown in dotted lines, and leading to the float or feed chamber is a supply pipe 7 for the purpose of supplying the chamber 5, the float 6 closing off a suitable valve to maintain a uniform height of water within the float or feed chamber 5.

Extending from the heater 2 near the bottom thereof is a pipe 8 to which pipe a pipe 9 passing from the float or feed chamber 5 is connected at the point 10, and as will appear from the drawing the pipe 9 is bent to form a complete circle 11 at a point below the heater 2 while a drain cock 12 is located in said pipe 9 to drain the same.

As will appear from the figure the pipe 8 passing from the heater 2 enters the steam tank 3 at the point 13 near the bottom of the tank 3 while a pipe 14 passes from the top of the heater and enters the steam tank 3 at the point 15, a drain cock 16 being arranged at the bottom of the steam tank 3 to drain the same.

The hot water tank 4 is arranged conveniently to the steam tank 3 and a coil 17 is located within the hot water tank 4 and passes out through the top thereof where it connects by means of a pipe 18 to the top of the steam tank 3, said coil 17 passing entirely through the hot water tank 4 and emerging therefrom at the bottom of the said tank where the said coil can be connected or piped to any convenient place for drawing off the distilled water within the coil 17.

The domestic boiler or storage tank 1 is connected to the hot water tank 4 by means of a short pipe 19 at the bottom of the boiler 1 which pipe 19 connects with the hot water tank 4 near the bottom of said tank 4, while a similar pipe 20 connects the boiler 1 with the hot water tank 4 near the top of the said boiler and tank. Entering the said pipe 20

between the boiler 1 and the hot water tank 4 is a pipe 21 which supplies hot water to the domestic hot water fixtures, while a cold water supply pipe 22 enters the boiler or storage tank 1 at the top thereof and extends to the point near the bottom thereof in such manner that the cold water supply enters the boiler or storage tank at a point near the bottom thereof. An opening 23 in the boiler or storage tank 1 is arranged near the top thereof.

Having thus described the several parts of the invention its operation is as follows: The water to be distilled passes into the float or feed chamber 5 through the supply pipe 7, and from the chamber 5 the water passes to the heater 2 through the pipe 9, circle 11 and pipe 8. The heater 2 being supplied in this manner the water entering the heater passes into the steam tank 3 through the pipe 14 and a circulation is effected between the heater 2 and the steam tank 3 by means of the pipe 8 and the pipe 14 at the top of the heater which enters the steam tank 3 at the point 15. This circulation is continuous as long as heat is applied to the heater and the water from the heater or steam tank 3 cannot pass back to the feed chamber 5 on account of the circular band 11 in the pipe 9 which effectually traps the water to prevent the hot water from the heater and steam tank 3 from passing through the pipe 9 and into the feed chamber 5. While this circulation between the heater 2 and the steam tank 3 is in progress the steam from the heater 2 and steam tank 3 passes out through the top of the steam tank 3 into the pipe 18 and into the coil 17, which coil is arranged within the hot water tank 4 where the steam is cooled and emerges from the bottom of the coil in the form of distilled water. This distilling process is in continuous operation as long as the water within the heater 2 is being heated.

Referring to the arrangement which heats the water within the domestic boiler or storage tank 1 it will be seen that the same is supplied through the pipe 22. The water supply entering the boiler 1 near the bottom thereof a circulation of water is effected through the hot water tank 4 and the boiler 1, the cold water passing through the pipe 19 at the bottom of the boiler into the bottom of the hot water tank 4 where the water in the hot water tank 4 is heated by means of the steam in the coil 17 and passes upwardly in the hot water tank 4, out through the pipe 20 and into the fixture supply pipe 21 or directly back into the boiler or storage tank 1. When therefore no water is passing out through the hot water fixture pipe 21 a continuous circulation of water is taking place within the boiler or storage tank 1 and the hot water tank 4 and the water is being heated by the steam in the coil 17. However,

as soon as any water is drawn through the fixture pipe 21 the same passes through the pipe 20 from the hot water tank 4 without first passing into the boiler or storage tank 1. Consequently the water passes to the fixture pipe at the time that it is the hottest which is when it circulates and reaches the top of the hot water tank 4 since as the water passes upwardly into the hot water tank 4 it is being continuously heated by the steam with- 75 in the coil 17. It will thus be seen that relatively a small quantity of water is always being heated within the hot water tank 4, which small quantity of water is sufficient at all times to supply the hot water fixtures, 80 and being relatively a small quantity the steam within the coil 17 can quickly heat the water within the hot water tank 4 without heating the entire volume of water within the boiler or storage tank 1. Consequently 85 a supply of hot water is at all times available for the hot water fixtures without first passing the water through the heater 2 as it is apparent from the foregoing description and the drawing that a separate water supply 90 is employed for the hot water fixtures which water supply never passes through the heater but is heated by means of the steam from the heater passing through the coil 17 arranged within the hot water tank 4. 95

Having thus fully described the invention what I claim as new and desire to secure by Letters Patent of the United States, is:—

A device of the character described comprising a heater, a source of water supply to said heater, a steam tank associated with said heater, said steam tank being piped to said heater near the bottom of the said steam tank and near the bottom of the said heater and piped to said heater at a point at the top of said heater and at a point in said steam tank remote from said first mentioned pipe from said steam tank, the same being arranged so as to effect a continuous circulation of water through the said heater and through the said steam tank when heat is applied to the said heater, a hot water tank associated with said steam tank and piped thereto at a point at the top of said steam tank and at the top of said hot water tank, a condensing coil within said hot water tank to which said pipe between the hot water tank and the said steam tank is connected, the said coil being arranged in such manner in relation to the steam tank and the heater so as to receive steam from the said steam tank and from the said heater, a storage tank associated with said hot water tank, said storage tank being relatively larger than the said hot water tank and piped to said hot water tank at a point near the bottom of said storage tank and said hot water tank and at a point near the top of said storage tank and said hot water tank, an independ- 130

ent source of water supply to said storage tank, said water supply being entirely independent of the water supply to said heater, said independent water supply to said storage tank entering the said storage tank at a point near the bottom thereof in such manner that the water so entering said storage tank will pass into said hot water tank through the lower piping connecting the said two tanks and will pass upwardly of the said hot water tank and around the said condensing coil and into the said storage tank through the upper piping between the said tanks in such manner that a continuous circulation is provided between the said storage tank and the said

hot water tank in order to effectually heat the water within the said storage tank, a hot water fixture supply pipe arranged to receive hot water from the upper portions 20 of said storage tank and said hot water tank, the whole being arranged in such manner that the water is delivered to the said hot water fixture pipe at a time when the said water is hottest, substantially as described 25 and for the purposes set forth.

In testimony whereof, I affix my signature, in presence of two witnesses.

DENNIS WILLIAM DALEY.
